UNITED STATES PATENT OFFICE.

ALEXANDER BULL, OF BROOKLYN, NEW YORK.

ALARM DEVICE.

1,262,012.

Specification of Letters Patent.

Patented Apr. 9, 1918.

Application filed July 18, 1917. Serial No. 181,188.

To all whom it may concern:

Be it known that I, ALEXANDER BULL, a citizen of the United States, and residing at Brooklyn, in the county of Kings and State 5 of New York, have invented certain new and useful Improvements in Alarm Devices, of which the following is a specification, such as will enable those skilled in the art to which it appertains to make and use the 10 same.

This invention relates to alarm devices for use in connection with receptacles or containers such as handbags, suit-cases and the like, in which valuable articles are carried 15 from place to place, and the object of which is to provide an alarm device which will be operated automatically in the event of the theft of, or an attempt to steal the handbag, or the like; a further object being to provide 20 an alarm device for the purpose above set out which will discharge a blank cartridge, and operate a bell or gong for a predetermined time.

The invention is fully disclosed in the 25 following specification, of which the accompanying drawing forms a part, in which the separate parts of my improvement are designated by suitable reference characters in each of the views, and in which:—

30 Figure 1 is a side view of a handbag with part of the construction broken away and showing my improvement in connection with said bag;

Fig. 2 a partial section on the line 2—2 35 of Fig. 1 and on an enlarged scale;

Fig. 3 a section on the line 3—3 of Fig. 2;

Fig. 4 a view looking in the direction of the arrow 4 of Fig. 5; and,

Fig. 5 a section on the line 5—5 of Fig. 4.

40 In Figs. 1, 2 and 3 of the drawing, 10 represents a handbag or container which is of the usual or any preferred form and construction and, in the practice of my invention, a container 11 is connected with the 45 bottom corner portion of the handbag 10 by a plurality of fastening devices 12 passed through the bag 10, and the walls of the container 11, and the inner end of said fastening devices are provided with thumb nuts 13, 50 whereby the container may be detachably connected with the bag 10, as will be readily understood.

A spring motor device 14 mounted between top and bottom frame members 15 and 55 16 is mounted in the bottom of the container 11, as shown in Fig. 2, said device

comprising a helical spring 17, one end of which is connected with a frame post 18 as shown at 19, and the other end of which is secured to a shaft 20 mounted in the frame members 15 and 16. A gear 21 is rotatably mounted on the shaft 20 above the spring 17, and a ratchet 22 is secured to the shaft 20 above the gear 21, and a pawl 23 is pivoted to the top of the gear 21, as shown at 24, and provided with a spring 25 for holding said pawl in engagement with the ratchet 22. A gear member 26 is mounted on a shaft 27 rotatable in the frame members 15 and 16, said gear member being in operative connection with the gear 21 as clearly shown in Fig. 4 of the drawing, and a toothed wheel 28 is mounted on the shaft 27 above the gear member 26. An oscillating pawl 29 is connected with a shaft 30 mounted in the frame members 15 and 16, said pawl being provided with curved end portions 31 and 32, which operate in connection with the toothed wheel 28 to permit the rotation thereof step by step only in the operation of the motor. A 80 hammer arm 33 is connected with the shaft 30 and provided on its free end with a head 34 which is adapted to operate in connection with a signal device consisting of a bell or gong 35.

The bell or gong 35 is provided on its inner side with a central stud 36 which is connected with an upwardly directed, threaded pin 37 mounted on a cross bar 38 secured to the bottom of the container 11, as 90 clearly shown in Fig. 3. The bottom of the container 11 below the bell or gong 35 is provided with an aperture 39 and the handbag or container 10 provided with a corresponding aperture 40.

95 The helical spring 17 of the spring motor device 14 may be wound up by a handle 41 connected with the top of the shaft 20, as clearly shown in Figs. 2 and 4, the pawl and ratchet construction operating to prevent 100 the rotation of the gear 21 in one direction. An arm 42 is connected with the shaft 30 and the free end portion thereof adapted to operate in connection with a pin 43 connected with a hammer device 44, as clearly shown 105 in Figs. 1 and 2.

The hammer device 44 is mounted in a frame 45 secured to the bottom of the container 11, said frame being provided with a plurality of upwardly directed bearing 110 members 46, 47, 48 and 49. The hammer device 48 is mounted to move longitudinally of

the frame 45 through the bearing members 47, 48 and 49. One end of the hammer device 44 is provided with an arm 50 with which is connected a cord or chain 51 which is adapted to pass upwardly through the bag or container 10 and out through an aperture 52 in the top portion of said bag and the end of which is provided with a loop 53, as clearly shown in Fig. 1 of the 10 drawing.

A coil spring 54 is mounted on the hammer device 44 between the pin 43 and the bearing member 48, said spring serving to move the hammer device longitudinally of 15 the frame 45 to explode or fire a blank cartridge 55 mounted in the bearing member 46, and the corresponding end of the hammer device 44 being provided with a central pin or projection 56 to accomplish this result, this construction being clearly shown in Figs. 1 and 2.

From the foregoing description, the operation of my improved alarm device will be readily understood when taken in connection with the accompanying drawing and 25 the following statement.

The normal position of the parts is shown in Figs. 1 and 2 of the drawing, in which position the hammer device 44 is moved 30 against the tension of the spring 54 and held in such position by the arm 50 which assumes a horizontal position and operates in connection with the bearing member 49, the top of which is open or fork-shaped in 35 form as shown at 57, as is also the top of the bearing member 48 as shown at 58 to permit the passage of the arm 50 through said bearing members when said arm is moved into a vertical position by means of the cord or chain 51. It will be noted that the pin 40 43 operates in connection with the arm 42 to hold the spring motor device in its inoperative position as clearly shown in Figs. 1, 2 and 3 of the drawing.

In the operation of carrying the bag or container 10 from place to place, the hand carrying the bag is passed through the loop 53, as will be readily understood, and an attempt to steal the bag, or take it from the 45 party carrying the same, would cause a pull on the cord or chain 51 which will move the arm 50 into a vertical position, and the pin 43 into a horizontal position, which operation will permit the spring 54 to move the hammer device into engagement with the blank cartridge 55 and explode the same, the charge passing through an aperture 59 in the end of the bag or container 10, and at the same time the arm 42 will be released to 50 put the spring motor device into operation, which will oscillate the hammer 33 to sound the bell or gong 35, as will be readily understood. The sounding of the bell or gong will be heard by reason of the apertures 39 65 and 40 in the container 11 and bag 10. The

container 11 forming a sound box as will be readily understood.

After the spring motor has performed its function, or the spring thereof is entirely unwound, the same may be rewound by manipulating the handle 41 and the hammer device 44 may be re-set into operative position by moving it against the tension of the spring 54 and rotating the same to bring the arm 50 into a horizontal position and the pin 43 into a vertical position and in engagement with the arm 42. The discharged cartridge or the shell may then be removed and a new blank cartridge substituted therefor. 70 75 80

While I have shown a construction for carrying my invention into effect, it will be readily understood that my invention is not limited to the details thereof herein shown and described, and various changes therein 85 and modifications thereof may be made, within the scope of the appended claims without departing from the spirit of my invention or sacrificing its advantages.

Having fully described my invention, what 90 I claim as new and desire to secure by Letters Patent, is:—

1. An alarm device for containers, means for supporting a blank cartridge in a container, a member mounted in said container 95 adjacent to and movable toward and from said cartridge, a spring adapted to move said member in one direction, a spring motor device, a signal device operated by said spring motor device, said spring motor device being 100 controlled by said member, means for locking said member under the tension of said spring, and means for releasing said member to permit its movement toward said cartridge to discharge the same. 105

2. An alarm device for containers, a device adapted to support a blank cartridge in a container, a member mounted in said container adjacent to and movable toward and from said cartridge, a spring adapted to 110 move said member in one direction, a spring motor device, a signal device operated by said spring motor device, means connected with said spring motor device and adapted to operate in connection with said member 115 to lock said device against movement, means for locking said member under the tension of said spring, and means for releasing said member to permit its movement toward said cartridge to discharge the same and release 120 said first named means to put the motor device into operation.

3. In a device of the class described, a bag or container, a casing mounted in the bottom portion thereof, said casing being provided with means for supporting a blank cartridge, a member mounted to move toward and from said cartridge, a spring for moving said member in one direction, a spring motor device mounted in said casing, 125 130

a signal device adapted to be operated by said device, means connected with said member for holding it in an operative position against the tension of said spring, means 5 connected with said motor device, and operating in connection with said member for locking said motor device against movement, and means connected with said first named means for moving it into position to release 10 said member and permit of its movement toward said cartridge to discharge the same.

4. In a device of the class described, a bag or container, a casing mounted in the bottom portion thereof, said casing being provided with means for supporting a blank cartridge, a member mounted to move toward and from said cartridge, a spring for moving said member in one direction, a spring motor device mounted in said casing, 20 a signal device adapted to be operated by said device, means connected with said member for holding it in an operative position against the tension of said spring, means connected with said motor device, and operating in connection with said member for locking said motor device against movement, and means connected with said first named means for moving it into position to release 25 said member and permit of its movement toward said cartridge to discharge the same and to release the means for locking the spring motor device against movement.

5. In a device of the class described, a bag or container, a casing mounted in the bottom portion thereof and adjacent to one wall thereof, said casing being provided with means for supporting a blank cartridge adjacent to said wall of the bag or container, the casing and wall of the container being 25 provided with an aperture adjacent to the support of said cartridge, a member mounted to move toward and from said cartridge, a spring for moving said member in one direction, a spring motor device mounted in 40 said casing, a signal device adapted to be operated by said device, means connected with said member for holding it in an operative

position against the tension of said spring, means connected with said motor device and operating in connection with said member for locking said motor device against movement, and means connected with said first named means for moving it into position to release said member and permit of its movement toward said cartridge to discharge the same through the apertures in said casing and the wall of said container. 55

6. In a device of the class described, a bag or container, a casing mounted in the bottom portion thereof adjacent to one side wall 60 thereof, the casing and one side wall of the container being provided with apertures, means for supporting a blank cartridge in said casing adjacent to said apertures, a rod mounted to move toward and from said cartridge, a spring mounted on said rod and adapted to operate it in one direction, means for locking said rod in an operative position against the tension of the spring, a spring motor device mounted in said casing, 70 said casing and the bottom of said bag or container being provided with an aperture, a signal device mounted in said casing adjacent to said apertures and said spring motor device and adapted to be operated by 75 said device, means connected with the motor device and operated in connection with said rod for locking said motor, and means for releasing the locking means of said rod to permit the movement thereof toward said 80 cartridge by said spring to discharge the same through the apertures in said casing and the side wall of the container and to release the means for locking the spring motor device against movement. 85

In testimony that I claim the foregoing as my invention I have signed my name in presence of the subscribing witnesses this 17th day of July 1917.

ALEXANDER BULL.
